UNITED STATES PATENT OFFICE

JOSEPH WITOLD KIZINSKI, OF ST. MARYS, WEST VIRGINIA

DESIGN FOR A COMBINED EGG CUP AND BEVERAGE TUMBLER

Application filed April 27, 1931. Serial No. 39,630. Term of patent 7 years.

To all whom it may concern:

Be it known that I, JOSEPH WITOLD KIZINSKI, a citizen of the United States, residing at St. Marys, in the county of Pleasants and State of West Virginia, have invented a new, original, and ornamental Design for a Combined Egg Cup and Beverage Tumbler, of which the following is a specification, reference being had to the accompanying drawings, forming a part thereof.

I claim:

The ornamental design for a combined egg cup and beverage tumbler as shown.

JOSEPH WITOLD KIZINSKI.
